Term of patent 14 years

(Cl. D87—5)

FIG. 1

FIG. 2

FIG. 3

FIG. 4

FIG. 1 is a top plan view of luggage or similar article embodying my new design;

FIG. 2 is an elevational view taken from the bottom of FIG. 1, the view from the top of FIG. 1 being the same;

FIG. 3 is an end elevational view looking at the left end of FIG. 1, the view from the right end being the same; and

FIG. 4 is a bottom plan view.

The essential features of my design reside in the full line showing thereof, and more particularly in the combination on luggage wherein the sides are provided with integral feet as aligned extensions of the sides as shown.

I claim:

The ornamental design for luggage or similar article, as shown and described.
